GERMICIDAL DETERGENT COMPOSITION
 Jack Blodinger, Monsey, N.Y., assignor to American Cyanamid Company, New York, N.Y., a corporation of Maine
 No Drawing. Filed Mar. 26, 1958, Ser. No. 723,942
 1 Claim. (Cl. 252—107)

This invention relates to a germicidal detergent composition containing hexachlorophene.

Hexachlorophene [2,2'-methylenebis(3,4,6-trichlorophenol)] is a well-known germicidal agent and has been used in soaps and various soap preparations. It is known that hexachlorophene is practically insoluble in water. It can be dissolved by the use of strong alkali resulting in solutions having a pH well above pH 9. Hexachlorophene can also be dissolved by the addition to soaps which have a pH above about 9. A solution of such high alkalinity, however, has a deleterious effect on the skin and frequent washings with such germicidal soaps or solutions can cause severe irritation of the skin.

It would be highly desirable to be able to prepare a germicidal detergent composition containing hexachlorophene in solution which would have a pH near that of the body, that is a pH of about 5-7, but heretofore this has not been possible because hexachlorophene is not soluble at such relatively low hydrogen ion concentrations.

I have now discovered a way of preparing germicidal detergent compositions containing hexachlorophene in solution at a desirably low pH of about 5-7 and in which the hexachlorophene is rendered soluble by the addition thereto of a certain specific class of nonionic surface active agents.

In carrying out the present invention, hexachlorophene is first dissolved in a nonionic surface active agent of the type described more particularly hereinafter. Preferably the hexachlorophene is dissolved in the nonionic detergent by heating at a temperature of from about 50 to 70° C. The resulting clear solution is then diluted with water to the desired concentration. A stable, germicidal solution is obtained which is stable even after adjusting the pH to between about 5-7 if necessary. The hexachlorophene is usually present to the extent of between about 1/2 and 5% by weight.

It is also within the scope of the present invention to incorporate a small amount of the antibiotic known as neomycin (cf. United States patent to Waksman No. 2,799,620) into the detergent composition. The nonionic surface active agent apparently renders the neomycin compatible with such solutions and prevents precipitation of the neomycin which normally occurs in such compositions when the pH is around neutrality. Usually a small amount, from about 0.1 to about 3%, of neomycin suffices for purposes of obtaining the additional bacteriostatic effect.

Among the suitable anionic detergents are the water-soluble higher fatty acid soaps (e.g. sodium lauryl sulfate, sodium salts of higher fatty acids derived from coconut oil, palm oil and tallow), and the sulfated and sulfonated organic detergents. Examples of the latter are water-soluble salts of higher alkyl aryl sulfonate (e.g. sodium dodecylbenzenesulfonate, sodium laurylbenzenesulfonate), higher alkyl sulfate detergent (e.g. sodium lauryl sulfate, potassium cetyl sulfate, triethanolamine lauryl sulfate, diethanolamine lauryl sulfate and ammonium lauryl sulfate), sulfuric acid esters of polyhydric alcohols incompletely esterified with higher fatty acids (e.g. sodium coconut monoglyceride monosulfate), sulfated higher fatty acid amides (e.g. sodium lauric monoethanolamide sulfate), etc. The anionic detergent is added for the purpose of increasing the detergency of the

2

composition and may be present to the extent of about 5 to about 40%.

The nonionic detergents found practical in solubilizing the hexachlorophene according to the present invention are the higher alkyl aryl polyglycol ethers, e.g. octylphenol or nonylphenol condensed with 6 to 30 moles of ethylene oxide such as the octylphenoxyethanol series of compounds sold under the trademark Triton, such as Triton X-100, Triton X-114, etc. and corresponding to the formula:

and wherein n is from 6-30, and the nonylphenoxypolyoxyethylene compounds sold under the trademark Igepal and corresponding to the formula:

wherein n is from 6-30. The nonionic surface active agent is usually employed in an amount ranging from about 1 to 40% by weight.

The invention will be described in greater detail in conjunction with the following specific examples in which the parts are by weight unless otherwise specified.

Example 1

A germicidal detergent composition is prepared by dissolving five parts of hexachlorophene in 10 parts by volume of Triton X-100 (reaction product of 9-10 moles of ethylene oxide with octylphenol) with heating at 60 to 80° C. The resulting clear solution is added to 100 parts by volume of water with stirring. A clear solution results and shows no change on standing for long periods of time at 5° C.

Example 2

A germicidal detergent composition is prepared by dissolving 0.15 part of neomycin sulfate in 40 parts by volume of water. 5 parts of hexachlorophene are dissolved in 10 parts by volume of Triton X-100. The hexachlorophene solution is added to the neomycin solution and 10 parts by volume of Triton X-114 (reaction product of 7-8 moles of ethylene oxide with octylphenol) are added along with 2.5 parts of Lanogel 41 (a water-soluble derivative of lanolin) and 20 parts by volume of triethanolamine lauryl sulfate. Distilled water is added to bring the volume up to 100 parts. A clear sparkling yellow solution with a pH of 5.5 is obtained. The resulting solution is stable as to the neomycin and hexachlorophene for a period of at least one year at a temperature of 25° C. and for two months at 42° C. or for one week at 56° C.

Example 3

A germicidal detergent composition is prepared as in Example 2 except that Triton X-114 is omitted. A storage stable composition is obtained.

Example 4

A germicidal detergent composition is prepared as in Example 2 except that Triton X-100 is omitted. A storage stable detergent composition is obtained.

Example 5

A germicidal detergent composition is prepared as in Example 2 except that 8 parts of Igepal CO-710 (nonylphenoxypolyoxyethylene) is used in place of the Triton X-100 used in Example 2. A storage stable composition is obtained.

I claim:

A germicidal detergent composition consisting essentially of from about 1 to about 40% of a nonionic surface

active agent selected from the group consisting of the reaction product of octylphenol with from 6 to 30 moles of ethylene oxide and the reaction product of nonylphenol with from 6 to 30 moles of ethylene oxide, from about 5 to 40% of a water-soluble organic anionic detergent, from about $\frac{1}{2}$ to about 5% of hexachlorophene, about $2\frac{1}{2}\%$ of a water-soluble derivative of lanolin, from about 0.1 to about 3% of a therapeutically effective form of neomycin, and sufficient water to total 100%, the resulting composition having a pH of between about 5 and about 7, and being storage stable for at least about a year at 25°C .
